[57] CLAIM

The ornamental design for a tire, as shown and de-
scribed.

DESCRIPTION

FIG. 1 is a perspective view of a tire showing our new
design, it being understood that the tread design is re-
peated throughout the circumference of the tire as
shown schematically by solid lines, the opposite side
being substantially the same as that shown;

FIG. 2 is a side elevational view thereof; and

FIG. 3 is a plan view thereof.
